INVENTOR

Thomas H. Beatty,
By Barn Barn & Crampton,
His attorney.

UNITED STATES PATENT OFFICE.

THOMAS W. BEATTY, OF CAREY, OHIO.

PORCELAIN-TUBE-HEADING MACHINE.

1,381,695.

Specification of Letters Patent. Patented June 14, 1921.

Application filed December 20, 1920. Serial No. 432,060.

To all whom it may concern:

Be it known that I, THOMAS W. BEATTY, a citizen of the United States, and a resident of Carey, in the county of Wyandot and State of Ohio, have made an Invention Appertaining to Porcelain-Tube-Heading Machines; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to machines for forming heads or shoulders on tubes of porcelain or other ceramic material.

An object of the invention is the provision of a machine of the character described which is simple and efficient in its construction and is operable to rapidly and successively feed tubes from a magazine or source of supply to a heading point, form heads thereon and then discharge the tubes preparatory to the next heading operation.

Further objects and advantages of the invention will be apparent from the following detailed description.

While the invention in its broader aspect is capable of embodiment in numerous forms, a preferred embodiment thereof is illustrated in the accompanying drawings, in which,—

Figure 1 is a top plan view of a machine embodying the invention, with the tube heading parts in heading position. Fig. 2 is a side elevation thereof. Fig. 3 is an enlarged longitudinal section of the left hand portion of the machine and Fig. 4 is an enlarged longitudinal section of the right hand portion of the machine, both taken through the longitudinal center of one of the heading units. Fig. 5 is a cross-section on the line 5—5 in Fig. 4, and Fig. 6 is a central longitudinal section of the outer end portion of one of the crank driven connecting rods.

Referring to the drawings, 1 designates a machine frame having the longitudinally extending transversely spaced beams 2, 2 connected together at their ends by cross pieces 3 and supported by legs or standards 4. The machine illustrated is provided with two heading units arranged side by side lengthwise of the frame and being of duplicate construction so that a description of

one will serve as a description of the other, 55 or for any number of units which it may be desired to employ.

The heading unit comprises a longitudinally movable placing plunger 5 located at one end of the machine for reciprocatory movements longitudinally thereof in suitable bearings 6. The forward or inner end of this plunger is provided at its under side with a spring finger 7 which extends longitudinally of the plunger and is fixed at its rear end thereto, as shown in Fig. 3. This finger projects at its forward end beyond the forward end of the plunger and is transversely broadened and curved in advance of the plunger end to provide a seat 7^a for 70 a porcelain when being advanced from supply position to upsetting position. The nose of the finger 7 is inclined or tapered on its outer end edge for the purpose hereinafter described. The plunger has its forward end 75 provided with a porcelain head receiving or upsetting recess 8. The recess 8 has a central opening 9 extending therefrom into the plunger lengthwise thereof.

A work holding magazine 10 is carried by 80 the frame 1 adjacent to the forward end of the plunger 5 when at the limit of its forward movement, and has an opening longitudinally therethrough, through which the plunger operates. When the plunger is at 85 the limit of its forward movement its forward end projects a short distance beyond the forward end of the magazine and when at the limit of its rearward movement the forward end of the plunger is retracted a 90 sufficient distance in the magazine 10 to permit a tube *a* therein to drop down in advance of the plunger onto the seat 7^a of the finger 7 to be carried forward with the finger at the next forward stroke of the plunger. 95

On the opposite end of the frame 1, in axial register with the plunger 5, is mounted a hollow or barrel like plunger 11 which is guided for movements longitudinally of the frame in bearings 12 mounted thereon. 100 The plunger 11 is provided at its forward or inner end with a reduced tubular head 13 having a removable or replaceable work receiving and upsetting end portion 14, which has its interior longitudinal opening of a 105 size to freely receive a tube *a* to be operated on and has its forward end adapted to abut against the forward end of the plunger 5.

and coöperate with the recess 8 thereof in upsetting the end of a tube and forming a head thereon as shown in Fig. 4.

A tubular stop member 15 is mounted within 5 in the plunger 11 and projects forward therefrom into the head 13 a desired distance to coact with and act as a stop for the adjacent end of the tube *a* being acted on. The stop tube 15 is adjustably carried at its rear end 10 portion by a pair of opposed clamps 16, 16 which extend crosswise of the frame top 3 through slots 17 in the opposite sides of the plunger barrel 11 and is secured to the frame top by screws 18. It is evident that 15 upon a loosening of the screws 18 the stop tube 15 may be lengthwise adjusted relative to the clamping plates and then secured in adjusted position by a tightening of the screws.

20 A core rod 19 is disposed within the rear end portion of the plunger barrel 11, being carried for movements therewith, and projects therefrom through the stop tube 15 and when in forward position, projects a distance 25 in advance of the tube end substantially equal to the length of a tube *a* to be operated on. The rear end of the rod 19 projects through the rear end of the barrel 11, being provided with a head 20, which 30 works in a socket 21 in the barrel end. A coiled expansion spring 22 encircles the rod 19 within the base portion of the socket and the head 20 of the rod to normally retain the latter retracted a predetermined distance 35 with respect to the barrel 11 for the purposes hereinafter described.

The plungers 5 and 11 have opposed inward and outward movements imparted in unison thereto from a rotation of a crank 40 shaft 23 having double cranks thereon, one for each plunger, and being driven from a shaft 24 through a worm and worm-wheel connection 25. The cranks are offset axially of the shaft so that a rod attached to each 45 may make a complete revolution without interfering with the other. The shaft 24 may be connected to a drive motor 26 or driven in any other suitable manner.

The crank 27 of the crank shaft is connected by a connecting rod 28 to an upright rocker member 29 that is pivoted at its bottom at 30 for rocking movements longitudinally of the frame and has its upper end connected by a link 31 to the plunger 5 of 50 the different units by a clamp 32. The throw of the member 29 is adjusted by changing the point of connection of the rod 28 with the member. A connecting rod 33 connects the crank 34 of the crank shaft 55 with an upright rocker member 35, which is pivoted at 36 to the base of the frame for rocking movements lengthwise thereof and is connected by a link 37 to the several plunger barrels 11 of the machine through 60 65 a clamping means 38. The wrist pin 39,

which pivotally connects the rod 33 and member 35, is journaled in a bearing block 40, which is mounted in a longitudinal guide 41 in the outer end of the rod 33 for reciprocatory movements lengthwise thereof. The outward movement of the block 40 in the guide 41 is cushioned by a coiled compression spring 42, which is disposed between the block and an outer adjustable thrust member 43, an adjustment of which, 70 to change the tension of the spring, is effected by a turning of a screw 44, which is threaded through the outer closed end of the guide 41. When the connecting rod 33 is near, but has not as yet reached the limit 75 of its inward stroke, the inward movement of the plunger 11 is stopped by the coaction of the clamping means 38 with a stop 48 (Fig. 4) fixed to the frame 1, the remainder 80 of the inward stroke of the connecting rod 85 33 then being permitted by the yielding action of the spring 42. It is thus evident that the plunger 11 and its forming head 14 have come to a stop during an inward movement thereof before the plunger 5 has 90 reached the limit of its inward movement, so that said latter plunger then advances alone to the point of coaction with the plunger head 14. The primary purpose of this is to cause the plunger 5 to first retract 95 from the formed head of a tube *a* before the plunger 11 begins its rearward or reTRACTING movement.

The plunger 11 at the rear end thereof, carries a vertically disposed lever 45 the upper end of which coacts with the outer end of the core-rod head 20. When the plunger 11 is near the limit of its inward movement the lower end of the lever 45 coacts with an adjustable stop 46 carried by the frame 100 so that during the remainder of the inward movement of the plunger 11 the lever 45 is actuated to move the core-rod 19 inward 105 relative to the plunger 11 against the tension of the spring 22 to advance the forward end of the rod into position to enter the registering opening 9 in the plunger 5. The core rod 19 normally is retracted so that its forward end does not project beyond the 110 end of the plunger head 14, thereby preventing the end of the rod from injuring or marring the soft material forming the tube *a* as the tube drops down from the plunger head 14 upon a retraction of the latter.

The operation of the machine is as follows:—

When the plungers 5 and 11 are at the limit of their outward or rearward movements a tube or work piece *a* in the magazine 10 drops down onto the subjacent finger seat 7^a in advance of the plunger 5. On the inward strokes of the plungers the work carrying finger 7 advances the work piece toward the advancing open end of the plunger head 14 in position for the work piece 115 120 125 130

to enter said head, the forward end of the finger 7 being caused to swing down and pass under the head 14 by the coaction of the tapered end thereof with the head. The 5 head 14 reaches its limit of forward movement in advance of the plunger 5 and then stands at rest by reason of the coaction of the clamp 38 with the stop 48 until the plunger 5 has advanced to coact with the 10 head 14 to upset the adjacent end of the work piece *a* into the forming recess 8, the work piece being held against endwise movement during such upsetting action by the coaction of its inner end with the stop tube 15. During the upsetting action the forward end of the core-rod 19 stands projected 15 in advance of the head 14 and into the opening 9 of the plunger 5 by reason of the advancing of the core-rod from its normal retracted position during the last portion of the advancing movement of the plunger 11, this action being occasioned by the lever 45 striking the stop 46. The plungers 5 and 11 then retract and the core-rod 19 returns to 20 its normal retracted position, and during this retracted movement the stop tube 15 acts as an ejector for forcing the formed work piece *a* from the forming head 14 and down into a receiving receptacle, which may be 25 placed below the forming position.

I wish it understood that my invention is not limited to any specific construction, arrangement or form of the parts, as it is capable of numerous modifications and changes 30 without departing from the spirit of the claims.

Having thus described my invention, what I claim as new, and desire to secure by Letters Patent, is,—

40 1. In a porcelain tube heading machine, a pair of coacting plungers movable toward and away from article operating position and adapted to coöperate to offset a work piece end, one plunger being operable to 45 advance a work piece into operative relation partially within the other plunger, and means for simultaneously imparting opposed reciprocatory movements to the plungers.

2. In a machine of the class described, a 50 pair of opposed reciprocally movable plungers adapted to coöperate to upset a tube end, one to receive a tube, and means operable to impart simultaneous opposed reciprocatory movements to the plungers.

55 3. In a machine of the class described, a pair of opposed reciprocatory plungers, one being hollow to receive a work piece advanced by the other plunger and both co-operating when advanced to upset an end of 60 a work piece, and means for imparting opposed reciprocatory movements to the plungers.

4. In a machine of the class described, a pair of opposed reciprocatory plungers, one 65 being hollow to receive a tube advanced by

the other and both coöperating when advanced to upset a portion of an inserted tube, stop means for preventing endwise movement of a tube during the upsetting action, a core piece for movement into and out of 70 the tube, and means for imparting simultaneous reciprocatory movements to the plungers and movement to the core pieces.

5. In a machine of the class described, a pair of opposed reciprocatory plungers, one 75 having provision for carrying a work piece from a point of supply to operating position and the other being adapted to receive the work piece and to coöperate with the companion plunger to upset a head on the work 80 piece, a core rod for entering a work piece when the plungers are advanced, and means for imparting opposed reciprocatory movements to the plungers and advancing and retracting movements to the core rod.

6. In a machine of the class described, a pair of opposed reciprocally movable plungers, one adapted to advance a work piece from receiving position into holding relation 85 to the other plunger, the plungers operating when advanced to form a head on a work piece, an adjustable stop means in coaction with an end of the work piece during the heading operation and independent of the plungers, and means for imparting opposed 90 movements to the plungers.

7. In a machine of the class described, a placing plunger having a work carrying finger adapted to receive a work piece at one position and to move it to a different position, a second plunger for receiving a work piece advanced by the first plunger and co-operating therewith to upset a portion of the work piece, means for imparting opposed reciprocatory movements to the plunger and a core member carried by the second plunger normally in one position thereto and automatically moved at a predetermined point in a movement of the second plunger to advance the core member a distance beyond the work upsetting end of the second plunger.

8. In a machine of the class described, a reciprocally movable plunger adapted to receive and hold a work piece, a second plunger movable toward and away from the work receiving end of the first plunger and adapted to coact therewith to head a work-piece, a work support yieldingly carried by the second plunger and projecting in advance thereof for carrying the work piece from one position and delivering it to the first plunger when the second plunger is moved inward and then to yield and pass under the first plunger, and means for imparting respective reciprocatory movements to the plungers.

9. In a porcelain tube heading machine, a pair of plungers mounted for opposed reciprocatory movements and adapted to co-

operate to head a work piece, a core rod carried by one plunger for movements therewith and for movements relative thereto, means for imparting opposed reciprocatory movements to the plungers, and means operable when the plungers are practically at the limit of their inward strokes to move the core rod to project its end from the work coacting end of the plungers and into the other plunger and then to retract it upon an initial movement of the plunger in the opposite direction.

10. In a machine of the class described, a pair of plungers mounted for opposed reciprocatory movements and having coacting portions for upsetting a portion of the work piece acted on thereby, a core-rod carried by one plunger for projecting through a work piece and for movements with the plungers and relative thereto, means for imparting opposed reciprocatory movements to the plunger, and means automatically operable to act on the core-rod when the plungers are near coacting position to advance the core-rod beyond the carrying plunger into the adjacent end of the opposed plunger and to retract the core-rod within its plunger when the plungers have outward opposed movements.

30 11. In a machine of the class described, a

pair of plungers mounted for opposed reciprocatory movements and operable to act together on a tube to upset a portion thereof, and means for imparting positive reciprocatory movements to one plunger and yielding reciprocatory movements to the other plunger, the yielding plunger having its movement stopped before the end of the driving stroke of the driving means.

12. In a machine of the class described, a magazine, a plunger reciprocally movable through said magazine to successively advance tubes therefrom to operating position, a second plunger reciprocally movable toward and away from the first plunger to cooperate therewith when in operating position to form a head on a tube, adjustable means for opposing the end thrust of the first plunger on a tube during the heading operation, core means movably carried by the second plunger and into the first plunger preparatory to the heading operation, means for imparting opposed reciprocatory movements to the plunger, and means for advancing and retracting the core means relative to its carrying plunger at predetermined points in the movement thereof.

In testimony whereof I have hereunto signed my name to this specification.

THOMAS W. BEATTY.
